UNITED STATES PATENT OFFICE.

WILLIAM KNUDSEN, OF FREMONT, NEBRASKA.

COMBINED CARBURETOR AND GOVERNOR.

Application filed September 29, 1924. Serial No. 740,651.

This invention relates to a combined carburetor and governor for internal combustion engines and has for its object to simplify, render more efficient and improve generally devices of this character.

The invention relates to the type of governor in which the throttle is moved toward closing position upon an increase in the velocity of the gas and is opened by the tension of a counteracting spring regulatable manually so that the speed of the engine may be controlled independently of the governor, while the carburetor is so designed as to produce a uniform and thorough intermixing of the component parts of the combustible gas under all conditions. The construction of the carburetor therefore lends itself to the maintenance of a volumetric efficiency throughout all speeds and under various loads.

A further object is to create and maintain a constancy of atmospheric pressure within the mixing chamber of the carburetor, thus insuring a uniform carburation irrespective of the variance in the atmospheric pressure due to change in altitude.

Various other objects and advantages of construction as well as the manner of operation of my improved device will be made more apparent as this description proceeds, especially when considered in connection with the accompanying drawings, wherein:

Figure 1 is an elevational view of a carburetor constructed in accordance with my invention; partly in section.

Fig. 2 is a longitudinal sectional view through the device taken substantially on the plane indicated by the line 2-2 in Fig. 1;

Fig. 3 is a horizontal sectional view taken substantially on the plane indicated by line 3-3 of Fig. 1;

Fig. 4 is a horizontal sectional view taken substantially on the plane indicated by the line 4-4 in Fig. 1; and,

Fig. 5 is a sectional view taken substantially on the plane indicated by lines 5-5 in Fig. 1.

Referring now particularly to the drawings, wherein like reference characters indicate like parts throughout the several figures, it will be noted that the reference character 10 indicates the outlet section of the carburetor suitably flanged as at 11 for connection with the intake manifold of an internal combustion engine. The lower edge of said outlet section is flanged and is se-

cured by means of bolts to the similarly flanged upper edge of the mixing chamber 12, the outer rim of a throttle valve 22 being clamped between the flanges. To the lower end of the mixing chamber is bolted a float chamber 13 having a float 14 which actuates a valve 15 disposed in an inlet nipple 16 connected to the source of fuel supply. An air inlet 17 is provided around the fuel inlet 16, which air mixes with the fuel in the mixing chamber 12 in a manner yet to be referred to.

Rigidly fixed to the mixing chamber 12 is a cone-shaped member 18 with which co-operates a movable cone 19, carried by the end of a hollow shaft or stem 20, extending longitudinally of the carburetor casing. This stem is squared as shown at 21, and slidably engages a squared sleeve portion 22' of the throttle valve 22. The stem 20 passes freely through a spider element 23 constituting a seat for the throttle valve 22. The stem 20 is supported adjacent its lower end by a central squared portion 23 of an air deflecting plate 24, which plate, as is apparent from Fig. 2, extends over the upper edges of the cone members 18 and 19. The stem is squared, as shown at 23' so as to slidably engage the deflecting plate 24. The stem 20 is guided at its upper end by the portion 24 of the carburetor casing. The connection between the stem 20 and the throttle valve 22 and deflecting plate 24 is such as to permit a relative vertical movement of the stem 20, but to cause the parts 22 and 24 to partake in any rotary movement of the stem.

When the stem 20 is rotated in a manner yet to be described, the inner cone 19, as well as the deflecting plate 24 are vertically adjusted. For this purpose the upper edge of the outer cone 18 is formed with a plurality of inclined faces 35, adapted to be engaged by an equal number of projections or lugs 36 formed on the upper edge of the inner cone 19. Consequently when the inner cone is rotated due to a rotation of the stem 20, the lugs 36 ride upon the inclined faces 35 and adjust the inner cone 19 vertically with reference to the outer cone. At the same time the deflecting plate 24 is vertically adjusted by means of co-operating slots 37 and pins 38 carried respectively by the plate 24 and wall of chamber 12. These slots 37 are inclined similarly to the faces 35 and when the plate 24 is rotated, due to a rotation of the stem 20, the slots 37 ride along

the pins 38 to vertically adjust the deflecting plate.

Extending longitudinally of the stem 20 is a needle valve 25 headed, having its upper end threadedly engaging the upper end of stem 20. The knurled head 26 permits adjustment of the needle valve, and lock nut 27 is provided for locking it in adjusted position.

- 10 Fixed to rotate with the stem 20 is a propeller 28, this propeller upon rotation, caused by the passage of gas through the carburetor, tending to rotate the stem 20 in a direction to close the throttle valve 22.
- 15 This action is opposed by a spring 29, one end of which is fixed to the stem while the other end is fixed to a rotatable collar 30, actuated by a manually controlled arm 31. It is understood that the arm 31 may be
- 20 controlled by any means convenient for the operator. Therefore, when the collar 30 is rotated in a direction to increase the tension of the spring 29 a greater velocity must be attained by the gas passing through the carburetor and acting upon the propeller 28 before the throttle valve 22 thereof will be closed.

In operation, air is drawn upwardly through the air inlets 17, as indicated by the arrows in Fig. 2, and is deflected by the air deflecting plate 24 over the upper edges of the cone members 18 and 19 and in close proximity thereto, thereby picking up fuel supplied to the space between these two members and carrying it to the mixing chamber. The fuel and air are thereby brought intimately in contact and flow upwardly past the throttle valve 22, whereupon the mixture strikes the propeller 28 and, owing to the pitch of the propeller blades, tends to rotate the propeller and stem 20 against the action of the spring 29. When a velocity has been attained by the mixture sufficient to overcome the tension of the spring 29 the throttle valve 22 is moved toward closed position, thus reducing the flow of the mixture. This will cause the engine to slow down, which, will decrease the vacuum and consequently slow down the velocity of the gas. The propeller blades will thereby be permitted to return toward their first position under the influence of the spring 29. A balance will soon be struck between the velocity of the gas and the spring to hold the engine at a uniform speed.

Rotation of the stem 20 by the propeller blades also effects the adjustment of cone 19 and deflector plate 24 as previously described.

- 60 The adjustment of cone 19 affords a positive control of the flow of fuel by the governor. Adjustment of the deflector plate simultaneously with the throttle valves causes the pressure in the mixing chamber to remain constant. In car-

buretors which do not control the air intake port simultaneously with the throttle valve the pressure in the carburetor will build up when the throttle valve is moved toward closed position, due to the velocity 70 of the air, and will decrease when the throttle valve is opened again until the velocity of the air has again reached its height. By closing the air port simultaneously with and to the same degree as the throttle valve 75 the piling up of the air, and consequent building up of pressure is minimized, and the pressure remains substantially constant. This results in more uniform sucking of the fuel from the jet, with consequent greater 80 uniformity in the mixture and smoother running of the engine, and this result is secured at all engine speeds and at any altitude.

The proportion of fuel and air may be 85 regulated by adjusting the needle valve 25 in the customary manner, it being possible to lock this needle valve in its adjusted position by means of a lock nut 27 whereby it moves in direct ratio to and with the stem 90 20. The position of the air deflecting plate 24 insures an intimate intermixing of the air and fuel as the air drawn in through the air inlets 17 is directed immediately over the space between the two cone portions 95 18 and 19. In this connection it should be noted that the fuel gathered by the air in its passage through the carburetor is directed by these cone members in an upward diverging direction and in a relatively thin sheet and that the direction of the fuel is abruptly altered by the air directed inwardly by the deflecting plate 24, thus further insuring an intimate and thorough intermixing of this air and fuel. Furthermore, 100 the cone member 19 is rotated by the rotation of the stem 20 so that the space between the cone members 18 and 19 is kept free of foreign matter which might tend to intercept the free passage of fuel there-through.

While an embodiment of this invention has been illustrated and described in some detail, it will be readily apparent to those skilled in this art that various modifications and rearrangements of this structure may be resorted to without departing from the spirit and scope of this invention and to this end reservation is made to make such changes as may come within the purview of the accompanying claims.

Having thus described my invention, what I claim is:

1. In a carburetor having a mixing chamber, an air inlet port for said mixing chamber, a fuel nozzle situated within said air inlet port, a deflector plate at said inlet port for directing inflowing air against the mouth of said nozzle, said deflector being adjustable relative to said nozzle for varying 125

the size of said inlet port, a throttle valve at the outlet side of said mixing chamber, a governor beyond said throttle dependent upon the velocity of flow of the mixture, 5 and connections between said governor, throttle, and deflector, whereby the positions of the throttle and deflector are simultaneously controlled by said governor.

2. In a carburetor having a mixing chamber, an air inlet port for said mixing chamber, an adjustable fuel nozzle situated within said air inlet port, a deflector plate at said inlet port for directing inflowing air against the mouth of said nozzle, said deflector being adjustable relative to said nozzle.

zle for varying the size of said inlet port, a throttle valve at the outlet side of said mixing chamber, a governor beyond said throttle dependent upon the velocity of flow of the mixture, and connections between 20 said governor, throttle, deflector, and nozzle, whereby the positions of said throttle, deflector, and the effective opening of the nozzle are simultaneously controlled by said governor.

The foregoing specification signed at Fremont, Nebraska, this 21st day of August, 1924.

WILLIAM KNUDSEN.
